HALOGENATED SALICYLANILIDE - HALOGENATED TRIFLUOROMETHYLDIPHENYL UREA SYNERGISTIC COMPOSITION

Herbert H. Reller and William E. Jordan, Cincinnati, Ohio, assignors to The Procter & Gamble Company, Cincinnati, Ohio, a corporation of Ohio
No Drawing. Filed Mar. 9, 1961, Ser. No. 94,437
1 Claim. (Cl. 167—30)

This invention relates to improved anti-bacterial agents. More particularly, it relates to anti-bacterial agents which comprise in combination a halogenated salicylanilide and a halogenated trifluoromethylidiphenyl urea compound.

The application of halogenated salicylanilide and trifluoromethylidiphenyl urea compounds as anti-bacterial agents individually has been disclosed in the art. The brominated salicylanilides have been employed as anti-bacterial agents in detergent compositions such as deodorant toilet bars, and laundering detergent products.

Anti-bacterial agents which have heretofore been employed in detergent compositions including the said halogenated salicylanilides display certain inherent deficiencies which detract from their efficacy in such applications.

Gram-negative organisms are common contaminants of the skin and other surfaces upon which anti-bacterial detergent usage has been found desirable and it is therefore essential to reduce the population of these organisms as well as gram-positive organisms to obtain the maximum beneficial effect. In general, anti-bacterial agents which have been found satisfactory for use in detergent milieu otherwise, display only slight activity against gram-negative organisms. Both the halogenated salicylanilide and halogenated trifluoromethylidiphenyl urea compounds are subject to this deficiency, neither compound displaying significant activity against gram-negative organisms at feasible use concentrations.

A disadvantageous characteristic of the widely used bisphenolic compounds is photo-sensitivity. When bis(3, 40 5,6-trichloro-2-hydroxyphenyl) methane and bis(3,4-dichloro-2-hydroxy phenyl) sulfide for example, are incorporated in a toilet detergent bar in concentrations as low as 0.5%, exposure to ordinary daylight results in an unsightly discoloration of the bar. To attain a minimum acceptable level of deodorant effectiveness using the bisphenols in such a bar, at least 2% by weight has been recommended. The degree of discoloration of detergent bars containing this level of bisphenolic compounds is sufficiently great that gold or yellow coloring material must be incorporated in the formulation for masking purposes.

Other anti-bacterial agents, though effective in aqueous solutions are incompatible with detergent actives or at pH values generally characteristic of detergent systems. Thus, the anti-bacterial activity of phenols for example, is almost completely lost in soap milieu. Quaternary ammonium compounds are similarly incompatible with soap and anionic synthetic detergents.

It is an object of this invention to provide a composition having a high level of anti-bacterial activity.

It is a further object of this invention to provide an anti-bacterial composition which is effective against both gram-positive and gram-negative bacteria.

It is a still further object of this invention to provide an anti-bacterial composition which is adapted to use in detergent milieu.

Other objects and improvements will become apparent from the following description.

In general, this invention comprises a synergistic combination of a halogenated salicylanilide and a halogenated trifluoromethylidiphenyl urea compound. "Synergistic combination" as used herein refers to a mixture of two or

2

more discrete agencies which display a degree of anti-bacterial activity which is greater than the sum of anti-bacterial activity of the agents taken independently. The ratio of the compounds of this invention can vary from 1:20 to 20:1.

The halogenated salicylanilides which find utility in this invention conform to the general structural formula:

10

15 wherein each X₁ represents hydrogen or halogen, X₂ represents a halogen, and Y represents hydrogen, halogen or trifluoromethyl.

The preferred halogenated salicylanilides which are encompassed by the above general formula include 3,5,4'-tribromosalicylanilide, 5 -bromosalicyl - 3,5 - di(trifluoromethyl)anilide, 5-chlorosalicyl-3,5-di(trifluoromethyl)anilide, 3,5-dichlorosalicyl-3,4-dichloroanilide and 5-chlorosalicyl-3-trifluoromethyl-4-chloroanilide. Other halogenated salicylanilides which come within the above general 25 formula and display synergistic activity in conjunction with the urea derivatives of this invention are disclosed by Bindler and Model in U.S. Patent 2,703,332, granted March 1, 1955. This patent further discloses a method for their preparation.

30 The trifluoromethylidiphenyl urea compounds which can be used in this invention are represented by the general structural formula:

35

wherein Z represents hydrogen, halogen or trifluoromethyl, X₁ represents halogen or ethoxy, X₂ represents hydrogen or halogen and Y represents hydrogen or trifluoromethyl. The preferred compounds of this group include 3-trifluoromethyl-4,4'-dichlorocarbamidine, 3-trifluoromethyl-3',4,4'-trichlorocarbamidine, 3,3'-bis(trifluoromethyl)-4-ethoxy-4'-chlorocarbamidine, and 3,5-bis(trifluoromethyl)-4-chlorocarbamidine. These and other operable halogenated trifluoromethylidiphenyl urea compounds are more fully described in U.S. Letters Patent 2,745,874, granted May 15, 1956.

45 The anti-bacterial efficacy of the synergistic combinations of this invention was established by determining their bactericidal activity in accordance with the methods developed by Cade and Halverson. (Cade, A.R., and Halverson, H.O., Soap, vol. 10, #9, page 25.) Anti-bacterial activity is expressed herein in terms of the percent reduction in number of viable microorganisms following exposure of a suspension of either *Staphylococcus aureus* as the representative gram-positive organism or

55 *Escherichia coli* as the representative gram-negative organism to a given concentration of the various anti-bacterial combinations for 10 minutes at 37° C. The relative effectiveness of the combinations is reflected in reduction of numbers of viable organisms.

60 The following examples are merely illustrative of the present invention and the invention is not limited to them. Examples I to VI immediately following are indicative of the synergistic anti-bacterial activity obtained by conjoint use of agents of the two classes disclosed herein, the specific agents being fairly representative of the classes in question.

Example	Concentration/micro-grams per ml.		Total	Percent Reduction		
	3-trifluoro-methyl-4,4'-dichlorocar-banilide	3,5,4'-tri-bromo salicylanilide				
				<i>E. coli</i>	<i>S. aureus</i>	
Control	10	0	10	25	0	
Ex. I.	9	1	10	33	26	
Ex. II.	7	3	10	37	30	
Ex. III.	5	5	10	40	40	
Ex. IV.	3	7	10	42	50	
Ex. V.	2	8	10	46	46	
Ex. VI.	1	9	10	42	30	
Control	0	10	10	4	0	

The activity of the mixtures of the above examples was determined in accordance with the method referred to above, i.e., sufficient anti-bacterial agent was added to a tube of FDA nutrient broth (U.S. Dept. of Agriculture Circular 198, December 1931, page 4) to attain the desired concentration. The suspending fluid and anti-bacterial agent were heated to 37° C. and inoculated with approximately five million cells of the test organisms. These mixtures were then incubated for 10 minutes and an aliquot was removed, diluted in 0.1% peptone water diluent, and placed on B.B.L. trypticase soy agar (supplied by Baltimore Biological Laboratories, Baltimore, Maryland). After solidification of the agar, the petri dishes were incubated for 24 hours and the number of colonies arising in that time was determined. The number of cells surviving exposure to the anti-bacterial was compared to the number contained in the original inoculum and the figure thus derived was adjusted in consideration of appropriate controls to give the percentage reduction value here employed. It can be seen that neither anti-bacterial agent by itself displays the degree of anti-bacterial activity attained with the combinations.

The efficacy of the mixture of this invention in soap and non-soap synthetic detergent milieu may be observed from the following examples.

Various concentrations of 3,5,4'-tribromosalicylanilide and 3-trifluoromethyl-4,4'-dichlorocarbanilide were added to an aqueous solution containing 250 micrograms/ml. of a neutral white, high grade soap consisting of a mixture of 80% sodium soap and 20% potassium soap derived from a blend of 70% tallow and 30% coconut fatty acids. Total anti-bacterial agent concentration was maintained at 5 micrograms/ml. or 2% by weight of the soap. The compositions thus prepared were tested for bactericidal activity using the method described supra. The following table presents the results of these tests, each value being an average obtained in several runs.

	Concentration/microgram per ml.		Total	Percent Reduction		
	3-trifluoro-methyl 4,4'-dichlorocar-banilide	3,5,4'-tri-bromo-salicylanilide				
				<i>E. coli</i>	<i>S. aureus</i>	
Control	5	0	5	60		
Ex. VII.	4	1	5	62		
Ex. VIII.	2.5	2.5	5	55		
Ex. IX.	1	4	5	66		
Control	0	5	5	10		

The percent reduction in numbers of organisms attributable to the respective anti-bacterial agents in soap solution is comparable to the values obtained when the same agents are tested in aqueous milieu.

Similar results are obtained when the other trifluoromethylidiphenyl urea compounds described as operable herein are employed in the soap matrix in place of 3-trifluoromethyl-4,4'-dichlorocarbanilide. Substitution of 3,4,4'-tribromosalicylanilide with the other halogenated salicylanilides of this invention, such as 5-bromosalicyl-3,5-bis(trifluoromethyl)anilide, 5 - chlorosalicyl - 3,5 - di-

(trifluoromethyl) anilide, 3,5-dichlorosalicyl-3,4-dichloroanilide and 5-chlorosalicyl-3-trifluoromethyl-4-chlorocarbanilide, results in comparable reductions in numbers of viable organisms. Further, variation of the soap matrix does not have any significant influence on the relative increase in activity attributable to the anti-bacterial agent.

Regular use of a soap bar containing 1% of a 1:1 mixture of halogenated salicylanilide and halogenated trifluoromethylidiphenyl urea of this invention results in substantial reduction in the bacterial population of the skin and thus markedly reduces body odor attributable to bacterial degradation of perspiration.

The mixtures of this invention have been found to significantly increase the anti-bacterial activity of non-soap synthetic detergent compositions including both anionic and nonionic and solid or liquid types. Although some of the detergents in the anionic group, for example, alkyl benzene sulfonate, have substantial anti-bacterial effect against gram-positive microorganisms, few have significant effect against gram-negative organisms. The incorporation of a small amount of halogenated salicylanilide-halogenated trifluoromethylidiphenyl urea mixtures of this invention in synthetic detergent compositions will effect an increase in anti-bacterial activity against gram-positive organisms and will impart significant levels of antibacterial activity against gram-negative organisms.

The anionic synthetic detergent which can be employed with this invention is generally defined as a water-soluble salt of an organic sulfuric reaction product having in its molecular structure an alkyl group containing from about 8 to about 22 carbon atoms and a radical selected from the group consisting of sulfonic acid and sulfuric acid ester radicals. Important examples of the synthetics of this group which may be benefited through the incorporation therein of the mixtures of this invention, are the sodium or potassium alkyl sulfates, especially those derived by sulfation of higher alcohols produced by reduction of glycerides of tallow or coconut oil; sodium or potassium alkyl benzene sulfonates, especially those of the types described in U.S. Letters Patents 2,220,099, granted November 5, 1940, and 2,477,383, granted July 26, 1949, in which the alkyl group contains from about 9 to about 15 carbon atoms; sodium alkyl glyceryl ether sulfonates, especially those ethers in which the alkyl group is derived from the higher alcohols obtained from tallow and coconut oil; sodium coconut oil fatty acid monoglyceride sulfonates and sulfonates, sodium salts of sulfuric acid esters of the reaction product of one mole of a higher fatty alcohol (e.g., tallow or coconut oil alcohols) and about three moles of ethylene oxide, and others known in the art, a number being specifically set forth in Byerly, U.S. Letters Patent 2,486,921, granted November 1, 1949, and Strain, U.S. Letters Patent 2,486,922, granted November 1, 1949.

The nonionic synthetic detergents hereinbefore described as beneficially affected by the anti-bacterial mixtures of this invention may be broadly defined as compounds produced by the condensation of alkylene oxide groups with an organic hydrophobic compound which may be aliphatic or alkyl aromatic in nature.

For example, a well-known class of nonionics to which significant levels of anti-bacterial activity will be imparted through the incorporation of minor amounts of a halogenated salicylanilide-trifluoromethylcarbanilide mixture is marketed under the trade name "Pluronic" by the Wyandotte Chemical Co. of Wyandotte, Michigan. These compounds are formed by condensing ethylene oxide with a hydrophobic base formed by the condensation of propylene oxide with propylene glycol.

Other nonionics which are suitable for use with the mixtures of this invention include the polyethylene oxide condensates of alkyl phenols, e.g., the condensation products of alkyl phenols having a straight or branched chain alkyl group containing from about 6 to 12 carbon atoms, with from about 10 to about 25 moles of ethylene oxide

per mole of alkyl phenol. The alkyl substituent in each compound can be conveniently derived from polymerized propylene diisobutylene, octane, or nonane or from any other natural or artificial source which will provide alkyl chains with the requisite number of carbon atoms as specified hereinbefore.

Other suitable nonionics may be derived by the condensation of ethylene oxide with the product resulting from the reaction of propylene oxide and ethylene diamine.

A minor amount of a 1:1 mixture of 3,5,4'-tribromosalicylanilide and 3-trifluoromethyl-4,4'-dichlorocarbanilide, for example, renders a composition containing any of the above detergents or mixtures thereof, antibacterially active against a broad range of microorganisms including some which are gram-negative.

Detergent compositions containing the anti-bacterial mixtures of this invention find utility in a variety of applications and physical forms as will be recognized by those skilled in the art. Such products may be used as toilet detergent bars, for example, the anti-bacterial mixture being present in amounts varying from 0.1% to 10% by weight of the total composition. Preferably, the bar would contain the said anti-bacterial mixtures in amount varying from .5% to 2% by weight of the total composition.

Example X

A milled toilet detergent bar was prepared in accordance with methods known and used in the art and having the following composition.

	Percent
Sodium alkyl glyceryl ether sulfonate (alkyl group derived from the middle-cut ¹ of alcohols obtained by catalytic reduction of coconut oil) -----	8.0
Potassium alkyl sulfate (alkyl group derived from the middle-cut ¹ of alcohols obtained by catalytic reduction of coconut oil) -----	20.0
Magnesium soap of 80:20 tallow:coconut fatty acids -----	16.7
Sodium soap of 80:20 tallow:coconut fatty acids -----	32.4
Inorganic salts (sodium and potassium chlorides and sulfates) -----	9.2
3-trifluoromethyl-4,4'-dichlorocarbanilide -----	1.0
3,5,4'-tribromosalicylanilide -----	1.0
Water and miscellaneous -----	11.7

¹ Middle-cut coconut alcohols having a chain length distribution substantially as follows: 2%—C₁₀, 66%—C₁₂, 23%—C₁₄, and 9%—C₁₆.

A marked reduction in body odor was noted by users of this bar in a panel comparison with a control bar comprised as above, but without the anti-bacterial agent. This deodorant effectiveness is also possessed by toilet detergent bars formulated as above but containing 3-

trifluoromethyl-3',4,4'-trichlorocarbanilide, 3,3'-bis(trifluoromethyl)-4-ethoxy-4'-chlorocarbanilide or 3,5-bis(trifluoromethyl)-4,4'-dichlorocarbanilide. Similarly, 3,5,4'-tribromosalicylanilide can be replaced by any of the other halogenated salicylanilides of this invention, such as 5-bromosalicyl-3,5-di(trifluoromethyl) anilide, 5-chlorosalicyl-3,5-di(trifluoromethyl) anilide, 3,5-dichlorosalicyl-3,4-dichloroanilide or 5-chlorosalicyl-3-trifluoromethyl-4-chloranilide without decreasing the deodorant efficacy of the product.

Example XI

A granular built synthetic anionic laundry detergent composition having the following formulation was prepared by conventional means.

	Parts
Sodium alkyl benzene sulfonate (the alkyl radical averaging about 12 carbon atoms and being derived from polypropylene) -----	17.5
Sodium tripolyphosphate -----	49.7
Sodium sulfate -----	13.3
Silicate solids -----	7.0
3-trifluoromethyl-3,4,4'-trichlorocarbanilide -----	.05
3,5,4'-tribromosalicylanilide -----	.05

Fabrics laundered in this product were imparted with substantial levels of anti-bacterial activity as was demonstrated by a marked reduction in surviving organisms when a suspension of viable test organisms were exposed to the laundered material.

The invention has been described above in conjunction with various illustrative examples of anti-bacterial compositions, toilet and laundry detergents. It will be obvious to those skilled in the art, however, that the anti-bacterial mixtures can also be beneficially employed in such products as tooth powder, toothpaste, mouth-wash, antiseptic ointment, foot powders and the like.

What is claimed is:

An anti-bacterial composition comprising in combination (1) 3,5,4'-tribromosalicylanilide and (2) 3-trifluoromethyl-4,4'-dichlorocarbanilide, and the ratio (1) to (2) being between 1:9 and 9:1.
